UNITED STATES PATENT OFFICE

JOHN J. HERLIHY, OF PITTSBURGH, PENNSYLVANIA

COMBINED RADIO CABINET AND LAMP

Application filed May 29, 1930. Serial No. 457,375.

In some, if not many, instances it is difficult to find a place in a room for a radio, as it is an added piece of furniture, and one of the objects of my invention is to combine a 5 radio cabinet and a floor reading lamp.

My combined radio cabinet and floor lamp comprises a hollow base, a hollow standard extending upwardly from the base, a hollow body supported on the upper end of the 10 standard, in which a station indicator and volume control and dial lamp are positioned and operative connections between the station and volume control and radio set, there being a suitable switch for the reading lamp and the radio circuits. 15

In the drawings,

Figure 1 is a front elevation of a combined radio cabinet and floor lamp embodying my invention.

20 Figure 2 is a side elevation of the same.

Figure 3 is a central vertical section of Figure 1.

Figure 4 is an enlarged detail vertical section.

25 Figure 5 is a section on the line 5-5 of Figure 4.

Figure 6 is a diagram of the circuits.

Figure 7 is an enlarged detail sectional view.

30 Figure 8 is a detail view.

The reference numeral 9 designates the hollow base of my radio cabinet, which is provided with a loud speaker opening 10 back of which is positioned a loud speaker 11. The 35 radio set 12 is also positioned within the base 9. The radio set, loud speaker, station indicator and volume control may be of any desired construction. In the claims, for sake of brevity, the term "radio set" will include the 40 loud speaker.

A hollow standard 13 extends upwardly from the top of the base to the upper end of which is secured a spherical body or casing which consists of the lower half 14 having a 45 screw threaded connection with the upper end of the standard as clearly shown in Figure 4, but of course any other suitable connection may be employed. This part 14 is provided with a radial flange 16 in the upper face of 50 which a groove 17 is formed, said flange being

also provided with screw threaded recesses 18; the other member 19 of the spherical body is likewise provided with a radial flange 20, in the under face of which is an annular groove 21, the counter part of groove 17. 55 This flange 20 is provided with openings 22 to receive the bolts 23 the screw threaded ends of which enter the recesses 18 in the flange 16 thereby binding the parts 14 and 19 together. A rim 24 is secured between the parts 14 and 19 with its edges sealed in the grooves 17 and 21, and is provided with a window opening 25 in front of the station indicator 26, back of which and in alignment with the window is positioned a dial lamp 27 supported on a bracket 28.

The station indicator 26 is keyed to a shaft 29, which shaft is provided with a bevel gear 30 keyed thereto. A station control 31 is revolvably mounted in the portion 14 and 70 is provided at its inner end with a bevel gear 32 that meshes with the gear 30, whereby the shaft 29 is revolved. As shown, this shaft 29 extends through the standard 13 and into the hollow base and is provided at 75 its lower end with a bevel gear 34 keyed to the shaft 35 journalled in brackets 36 within the hollow base 9, said shaft 35 having a drum 37 keyed thereon. This drum 37 is provided, preferably, with two grooves in 80 each of which one end of the wires, or belts 38 are firmly secured by pins 39, as best seen in Figure 7, the wires having substantially one turn around the drum, said wires running over sheaves 40, with their other ends secured in a similar manner to a drum 41 mounted on a shaft 42 connected with the condenser or tuning device of the radio set. 85

The upper half 19 of the spherical body is provided with a screw threaded opening 90 in which a reading lamp support 43 is secured, said support having lamp sockets 44 to receive the lamps 45, there being the usual chain pulls 46 for the lamp sockets.

As shown in Figure 6, and in Figure 3, 95 a single lead in wire 47 serves for the radio set and the reading lamp. This wire, or conductor 47 is directly connected with the reading lamp socket 45, there being a minus circuit 48, which as will be hereinafter de- 100

scribed is common to the reading lamp, the dial lamp, and the radio set. A circuit 49 is tapped into the circuit 47 and leads to the radio set switch 50, which switch when 5 thrown contacts with contact point 51 and thus completes a plus circuit 51 to the radio set and a plus circuit 52 to the dial lamp 27.

The specific circuits described, the radio set, the reading lamp, dial lamp, station indicator, and volume control may be changed 10 to any desired standard plan, my broad invention being the combined radio cabinet and floor or other lamp.

A is the circuit between the volume control 15 and the radio set.

What I claim is:

1. In a radio apparatus, a base, a hollow standard rising from the base and comprising upper and lower sections, a radio receiver 20 including a loud speaker and a tuner arranged in said base, a casing disposed between and uniting the sections of the standard and having a display opening, a station indicator in said casing movable with relation to said display opening, gearing in the base for adjusting the tuner, operating means 25 actuable from the exterior of the casing for operating the station indicator, and means extending through the standard between the base and casing and connecting said operating means in the casing and the gearing in the base for simultaneous actuation.

2. In a radio apparatus, a base, a hollow standard rising from the base and comprising upper and lower sections, a radio receiver 30 including a loud speaker and a tuner arranged in said base, a casing disposed between and connected to the standard sections and comprising spaced sections connected to said members and to each other and a rim member held between said sections and provided with a display opening, a station indicator in said casing movable with relation to said display opening, gearing in the 35 base for adjusting the tuner, operating means actuable from the exterior of the casing for operating the casing indicator, and means ex-

tending through the standard between the base and casing and connecting said operating means in the casing and the gearing in the base for simultaneous actuation.

3. In a radio apparatus, a base, a hollow standard rising from the base and comprising upper and lower sections, a radio receiver including a loud speaker and a tuner arranged in said base, a casing disposed between and uniting the sections of the standard and having a display opening, gearing in the base including drums and a cable extending therebetween for operating the tuner, an operating element carried by the casing and actuatable from the exterior thereof, a station indicator in the casing movable with relation to the display opening thereof, and a shaft connected thereto and extending through the lower section of the standard between the base and casing and in gear with the operating element and with the tuner adjusting gearing in the casing.

4. In a radio apparatus, a base having a transversely flat open front, a closure for said open front provided with a sound emission opening therein, a radio receiving set within the base including a tuner and a loud speaker, the latter being disposed behind said opening, gearing in the base for actuating said tuner, a standard rising from the base and comprising upper and lower sections, a casing disposed between and uniting said standard sections and having a display opening therein, an indicator in said casing movable with relation to said display opening, a shaft in gear with the gearing in the base and connected with the indicator, said shaft extending between the base and casing through the lower section of the standard, actuating means for said shaft mounted on the casing and operable externally thereof, a lamp in the casing, an electric circuit including the receiver and the lamp, and a switch device for opening and closing said circuit.

In testimony whereof I affix my signature.

JOHN J. HERLIHY.
